UNITED STATES PATENT OFFICE.

ALBERT GLASER, OF NEW ORLEANS, LOUISIANA.

ELECTRICAL SWITCH.

Application filed January 26, 1922. Serial No. 531,975.

To all whom it may concern:

Be it known that I, ALBERT GLASER, a citizen of the United States, and a resident of New Orleans, in the parish of Orleans and State of Louisiana, have invented certain new and useful Improvements in Electrical Switches, of which the following is a specification.

This invention relates to an electrical switch.

As is well known jacks and plugs are commonly employed in wireless telegraphy for establishing connection between the receiving circuit and different amplifying circuits or detector circuits, it is customary to withdraw the plug from one jack and then insert it in another jack for including the circuits desired with the receiver. As is obvious the lapse of time occurring during the transferring of the plug from one jack to another will result in the loss of several letters and possibly a word at the receiver.

With the above in view it is the object of the present invention to associate a plug with a plurality of jacks in such a manner that the contact end of the plug may be swung for establishing individual connection with either of the jacks associated therewith for operating the same in an easy and quick manner, and thereby reducing the lapse of time in shifting the plug from one jack to another to a minimum.

It is also an object of the invention that the plug be adapted to be removed from its mounting and another plug of the same structure substituted therefor, and thereby permitting a number of receivers to be connected and operated by the same switch or the set of jacks.

Other objects and objects relating to details of construction, combination and arrangement of parts will hereinafter appear in the detailed description to follow.

The invention is illustrated by way of example in the accompanying drawings, in which:—

Figure 1 is a plan view of a switch constructed in accordance with the present invention,

Figure 2 is a side elevation of the same,

Figure 3 is a vertical longitudinal sectional view of the same,

Figure 4 is a longitudinal section view of a plug which may be employed with the switch,

Figure 5 is a group perspective view of the elements comprising the plug,

Figure 6 is a vertical sectional view taken on the line 6—6 of Figure 4.

Referring to the drawings more particularly, 10 indicates generally a base plate which is preferably sector in shape, the end of which is bent upwardly as at 11 and said end terminating in an L-shaped portion generally indicated by the reference numeral 13, the vertical portion of which is recessed as at 14. In the recess 14 there is pivoted a sleeve 15 by the means of screws 16, said sleeve being adapted for receiving the plug generally indicated by the reference character B.

Upon the plate 10 there is secured a plurality of jacks generally indicated by the reference character A, said jacks extending radially of the plate and each jack consisting in an upper and lower plug contacting spring finger 18 and 19 respectively, between which is interposed a pair of supplemental spring fingers 20. The supplemental spring fingers and likewise the plug contacting spring fingers are insulated from each other by suitable fiber plates, or the like, as at 21 and the unit as a whole secured to the base plate 10 by the means of a pair of machine screws, said screws each being preferably surrounded by a sleeve 23. Also the outer end of each supplemental spring finger 20 and likewise the same end of the plug contacting spring fingers 18 and 19 terminating in the usual hook shaped portion 24 adapted to permit the easy connection of a wire therewith. The inner ends of the plug contacting fingers 18 terminate in a downwardly and then upwardly bent tip portion 25, while the fingers 19 therebeneath terminate in a similar portion as at 26, which however opposes the tip 25, as shown, and which is disposed slightly forward to the associated tip 25. Each upper and lower plug contacting finger is also formed with a point 27 which is adapted to normally contact with its associated supplemental spring 20 and establish an electrical connection therewith. Also the outermost plug contacting fingers 18 may be cut away as at 28 if so desired.

Referring particularly to the plug B, as shown in Figures 4 to 6 inclusive, 28 indicates what may be generally termed as the plug portion, said plug portion comprising 130

a sleeve which is reduced at its forward end as at 29 and which is enlarged at its rear end as at 30. Upon the sleeve there is fitted a tubular handle member 31, the rear end of 5 which abuts the enlargement 30 and its forward end abuts the screw collar 32 threaded upon the sleeve as shown. The sleeve or plug member 28 is also recessed as at 33, and in the forward end of the sleeve there is positioned a tubular insulating member 34 which is cut away as at 35 to correspond with the recess 33 of the sleeve 28. The member 34 is of insulating material and has disposed therein a stem 36 which terminates at its forward end in a ball 37. To the rear end of the stem 36 there is suitably connected a wire 38 by the means of a screw 39; and also to the sleeve or plug portion 28 there is similarly connected a second wire 40. The wires 10 40 and 38 extend through the rear end of the plug member 28, and the bushing 41 threaded in said rear end of the plug member and then extended in a cable 42.

In the use of the present switch arrangement the plug B may be connected to a receiver in a wireless apparatus. As before stated the jacks A may be connected with the amplifying and detector circuits. Each jack A may be utilized for establishing one, 15 or more circuits and maintaining them closed if desired, that is, a circuit might be connected and maintained closed through the top finger spring 18 and its associated spring 20 of one jack, while another circuit 20 may be maintained closed through the spring finger 19 and the remaining supplemental spring finger 20. With this arrangement when the plug B would be swung to a position, as shown in Figure 3 of the drawings, 25 the two closed circuits mentioned would be opened and the spring fingers 18 and 19 connected in series with the circuit connected

with the plug B. All other connections may be established through the use of the jacks A, that is, other combinations of circuits are provided through these jacks. 45

It is also to be recognized that the plug B is freely removable from its mounting and thereby permits other plugs of the same cross-section to be inserted, and in this manner enabling a number of the receiver circuits to be manipulated by the same set of jacks or switch.

While I have described a particular use of the invention it is to be understood that I am not to be so limited as it is clearly obvious the same switching device may be used for controlling a plurality of electrical circuits associated or employed in connection with radio equipment other than that used in wireless telegraphy.

I claim:

1. A switch of the character described, comprising a base plate, a plurality of spaced jacks secured to said base plate in diverging relation with each other, a sleeve pivoted for horizontal swinging movement beyond the free ends of said jacks, and a plug removably held by said sleeve adapted to be brought into alignment with each of 55 said jacks for operating the same.

2. A switch of the character described, comprising a base plate, sector in shape, having in U-shaped flange formed at its inner ends, said flange having a recess in its vertical portion, a sleeve pivoted for horizontal swinging movement in said recess, a plug rotatably held by said sleeve, and a plurality of jacks secured to said base plate so that 75 their free ends are disposed for receiving said plug when swung upon its pivot and thereby permitting each of the jacks to be operated individually.

ALBERT GLASER.
